UNITED STATES PATENT OFFICE.

GEORGE F. VOITH, OF PHILADELPHIA, PENNSYLVANIA.

REPEATING DEVICE FOR TALKING-MACHINES.

1,248,041.

Specification of Letters Patent.

Patented Nov. 27, 1917.

Application filed March 27, 1917. Serial No. 157,823.

To all whom it may concern:

Be it known that I, GEORGE F. VOITH, a citizen of the United States, residing at Philadelphia, in the county of Philadelphia and State of Pennsylvania, have invented certain new and useful Improvements in Repeating Devices for Talking-Machines, of which the following is a specification.

My invention consists of a repeating device for talking machines. One object of my invention is to provide a device which can be quickly and easily attached to a talking machine and which will efficiently operate to effect the movement of the reproducing elements of the talking machine to repeat the record.

Another object is to so construct my invention that it will not injure any of the several parts of the talking machine or record.

Another object is to so design my invention that it will be durable and of comparatively simple construction.

These objects, and other advantageous ends which will be described hereinafter, I attain in the following manner, reference being had to the accompanying drawings in which—

Figure 1 is a top plan view of my improved repeating device.

Fig. 2 is a section on the line 2—2 of Fig. 1.

Fig. 3 is a section on the line 3—3 of Fig. 1.

Fig. 4 is a section on the line 4—4 of Fig. 1.

Fig. 5 is a section on the line 5—5 of Fig. 1.

Fig. 6 is a section on the line 6—6 of Fig. 1.

Fig. 7 is a fragmentary sectional elevation showing certain of the elements of my invention.

Fig. 8 is a section on the line 8—8 of Fig. 7.

Fig. 9 is a fragmentary plan view showing a modification of certain of the parts illustrated in Fig. 1.

Fig. 10 is a section on the line 10—10 of Fig. 9.

Fig. 11 is a section on the line 11—11 of Fig. 9, and

Fig. 12 is a view of a cross arm which I may employ in combination with the ordinary form of phonograph needle and in-

stead of the specially constructed needle shown in Figs. 7 and 8.

Referring to Figs. 1 to 8 inclusive, 1 represents a plate which is preferably made of sheet metal and includes a ring section 2 and a solid section 3. The solid section 3 has a turned edge 4 upon which a section 5 slides. This section 5 has a projection 6 provided with a hole 7 through which the turn table post of the talking machine extends and thus provides the center of rotation for the plate 1.

The section 5 is notched, as shown at 8, on its inner edge for the engagement of a spring detent 9 which is secured to the solid section 3 of the plate 1, the object being to hold the centering section 5 in various positions on the turned edge 4.

The solid section 3 forms a support for a plurality of rails 10, said rails being 75 soldered throughout a portion of their length adjacent the turned edge 4 as illustrated at 11. These rails are preferably made of thin resilient metal, their inner ends 12 being freely movable in a plane 80 parallel with the upper surface of the plate 1.

An inner rail 13 is secured to the solid section 3, and at one end projects beyond the turned edge 4 as shown at 14. An extreme 85 outer rail 15 is secured, preferably throughout its entire length, to the solid section 3.

The ends 16 of all of the rails extend within the ring section 2, and the upper edges of these ends of the rails slant or taper as shown at 17 (see Figs. 2, 3, and 8). As illustrated in Fig. 1, all of the rails are curved, and at their ends 16 are spaced farther apart than at the ends 12. The curvature and arrangement of the rails is 95 such that at the ends 16, the rails are spaced relatively far apart and gradually become closer together until all the intermediate rails open into the space 18 between the rail 13 and rail 15. Thus, the rails are located 100 in a substantially spiral formation as clearly illustrated in Fig. 1.

The ring section 2 has an overturned portion 19 on its upper surface which provides a slideway for a carriage 20. This carriage 105 20 supports a member 21 which in turn provides a guideway for an arm 22 which is preferably angular in cross section as clearly illustrated in Fig. 5.

The member 21 can be soldered or other- 110

wise secured to the carriage 20, so that said member and the carriage move as a unit within the slideway 19, and the arm 22 is designed to slide longitudinally toward and from the center of the plate 1. A coiled spring 23 has one end attached to the carriage 20 and the other end attached to the plate 1 as shown at 24. This spring 23 serves as a buffer or to compensate for the jar caused by the engagement of the arm 22 with certain of the recording elements of the talking machine as will hereinafter be more fully described.

In the use of my invention, I preferably provide a four-pointed needle, one leg of which can be inserted within the usual needle carrier on a talking machine so that the point 25 will engage the grooves of the record, the other leg 26 extending substantially at right angles thereto and being operative when engaged by any of the tapered portions 17 of the rails to be lifted so that the point 25 is raised above the level of the record, and also above the upper surface of the plate 1.

I preferably cover the bottom of the plate 1 with soft material such as felt or other cloth, and provide a balancing pad 27 which depends from the lower surface of the plate 1. The location of this pad is dependent upon the balancing point of the entire device and can be made of soft material so as not to injure the record by coming in contact with it.

In order to properly locate this pad, I first balance the device, for example as upon the end of a finger of one hand, and on the spot upon which the device balances on the finger I paste or otherwise secure the balance pad. The construction is such that the balancing pad normally forms the sole support of the device on the record so that the major portion of the device is held in a position spaced from the upper surface of the record. Furthermore, the general shape of the device is such that the balancing point upon which the pad is mounted is adjacent the center of the plate 2 so that the pad rests upon the record near the center of the latter where there are no sound reproducing grooves. In this manner the reproduction portion of the record is not injured by the rotation of the record under the device, since the record engages the balancing pad and rotates thereunder.

In the operation of my invention, the plate 1 is placed upon the record of the talking machine, the post of the talking machine extending through the hole 7 of the centering section 5, the space 18 being located adjacent the initial recording groove of the record. This position can be attained by sliding the section 5 longitudinally along the turned edge 4 and against the action of the spring detent 9. The arm 22 is then slid

until its inner end 28 lies directly above the last recording groove of the record. The needle point 25 is then inserted in the usual manner within the outer groove and the needle carrier is permitted to rest against the edge 29 of the arm 22.

The rotation of the record will cause the needle carrier to move inwardly along the edge 29 of the arm 22 during which time the record is being produced. When the needle carrier has reached the end 28 of the arm 22 and becomes free thereof, the record will rotate the entire plate 1 and cause the transversely extending arm 26 of the needle to be engaged by the tapered portions 17 of the rails which are moving within the path occupied by the needle.

The engagement of the tapered portions of the rails will raise the needle from the grooves of the record and will also raise the needle point above the upper surface of the plate 1 as clearly shown in Figs. 7 and 8, so that the needle point will not be injured by coming in contact with the top of the plate or with any portion thereof.

As the plate rotates, the needle will follow the path provided by the rails upon which it rests and will eventually ride upon the upper edges of the rails 13 and 15 where the latter forms the space 18 and are close together as shown on the left hand side of Fig. 1, thus the arm 22 will again engage the needle carrier and the rails 13 and 15 will return the needle to the initial recording groove and the operation will be repeated.

The spring 23 serves to prevent any harsh action or injury to the machine, and relieves the jar which would otherwise occur if the arm 22 were made permanent or secured directly to the plate 1.

It will be noted that my invention can be employed to suit records of various diameters, it only being necessary to move the centering slide 5 along the turned edge 4, and furthermore, the arm 22 is made sufficiently long to accommodate various areas of recording grooves on various size records.

Instead of having the specially constructed four pointed needle as above described, I can use a cross arm for example, as shown in Fig. 12, and this cross arm can be used with the usual form of single pointed needle now in common use merely by inserting the stem 30, together with the needle, within the needle carrier, and when so used the transversely extending arms 31 and 32 will be engaged by the tapered portions 17 of the rails and the needle will be lifted above the record and above the top surface of the plate 1.

In the form of my invention shown in Fig. 9, I have illustrated a spring 33 which is preferably made of flat resilient metal and this spring is positioned to the rear of the arm 22. The spring 33 is mounted in

supports 34 on the ring section 35 which corresponds in all other respects with the ring section 2 above mentioned.

Furthermore, in this form of my invention, instead of the arm 22 being pulled by a spring, as for example the spring 23, it is backed by the spring 33, and the spring 33 therefore acts to cushion and to take up the jar caused by the engagement of the arm 10 22 with the needle.

In all other respects the form of my invention shown in Fig. 9 is similar to that above described in connection with Figs. 1 to 8 inclusive, and I have therefore given 15 similar parts corresponding reference numerals.

By mounting the rails so that their inner ends are free to flex, I avoid any harsh scraping action and undesirable noise, since 20 the rails gradually compel the needle to be returned to the initial position.

Furthermore, by balancing the plate 1, it is normally kept free of the reproducing portion of the record and the weight of the 25 parts is such that the balancing pad comes within the space of the record not occupied by the reproducing grooves. My invention is therefore extremely practical and effectively operates for the purposes set forth.

30 While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what 40 I claim as new and desire to secure by Letters Patent is:

1. A repeating device for talking machines comprising a plate, rails mounted on said plate, and means for engagement with a 45 reproducing element of the talking machine during the reproduction of a record, said rails having portions designed to lift said reproducing element above the plane of movement of the plate and other portions 50 designed to return said element to the initial reproducing portion of the record, substantially as described.

2. A repeating device for talking machines including a plate, rails made of resilient material and secured for a portion 55 of their length to said plate and having other portions freely movable in a plane parallel with the top surface of the plate, substantially as described.

60 3. A repeating device for talking machines including a plate, rails made of resilient material and secured for a portion of their length to said plate and having other portions freely movable in a plane 65 parallel with the top surface of the plate,

outer and inner rails forming an enclosure for said first-mentioned rails and between which said free ends of the first-mentioned rails are designed to move, substantially as described.

4. A repeating device for talking machines, comprising a plate, rails mounted on said plate, means for engagement with a reproducing element of the talking machine during the reproduction of a record, 70 said rails having portions designed to lift said reproducing element above the plane of movement of the plate and other portions designed to return said element to the initial reproducing portion of the record, 75 and a movable centering section mounted on said plate, substantially as described.

5. A repeating device for talking machines, comprising a plate, rails mounted on said plate, means for engagement with a 80 reproducing element of the talking machine during the reproduction of a record, said rails having portions designed to lift said reproducing element above the plane of movement of the plate and other portions 85 designed to return said element to the initial reproducing portion of the record, a centering section slidably mounted on said plate and having a notched portion, and a detent secured to said plate and designed to engage 90 the notch portion of this centering section, substantially as described.

6. A repeating device for talking machines comprising a plate, rails mounted on said plate, a carriage movable on said plate, 100 an arm slideable relatively to said carriage, and resilient means connecting the carriage with the plate, said arm being designed to engage a reproducing element of the talking machine during the reproduction of a record 105 and to free itself of said element when the record has been completely reproduced, substantially as described.

7. A repeating device for talking machines comprising a plate, rails mounted on 110 said plate, a carriage movable on said plate, an arm slideable relatively to said carriage, resilient means connecting the carriage with the plate, said arm being designed to engage a reproducing element of the talking 115 machine during the reproduction of a record and to free itself of said element when the record has been completely reproduced, said rails having portions designed to lift 120 said reproducing element above the plane of movement of the plate and other portions designed to return said element to the initial reproducing portion of the record, substantially as described.

8. A repeating device for talking machines comprising a plate, rails mounted on 125 said plate, a carriage movable on said plate, an arm slideable relatively to said carriage, resilient means connecting the carriage with the plate, said arm being designed to en- 130

gage a reproducing element of the talking machine during the reproduction of a record and to free itself of said element when the record has been completely reproduced, 5 said rails having tapered end portions designed to lift said reproducing element above the plane of movement of the plate, and other portions designed to return said element to the initial reproducing portion of the record, substantially as described.

9. A repeating device for talking machines, comprising a plate, rails mounted on said plate, means for connection with the talking machine needle carrier having a 15 transversely extending leg, means carried by said plate for engagement with said first means, said rails having portions designed to lift said transversely extending leg and thereby raise the needle above the record and 20 plate, said rails having other portions designed to return said needle to the initial reproducing portion of the record, substantially as described.

10. A repeating device for talking ma-

chines, comprising a plate, rails mounted on 25 said plate, a needle for connection with the talking machine needle carrier having leg portions arranged transversely to each other and provided with points, certain of the leg portions being in alignment with the needle 30 carrier while the other leg portions are arranged transversely thereto, means carried by said plate for engagement with said needle, said rails having portions designed to lift said transversely extending leg portions 35 of the needle and thereby raise the needle above the record and plate, said rails having other portions designed to return said needle to the initial reproducing portion of the record, substantially as de- 40 scribed.

In testimony whereof I have signed my name to this specification in the presence of two subscribing witnesses.

GEORGE F. VOITH.
